UNITED STATES PATENT OFFICE

2,556,164

APPARATUS FOR MAKING STRANDED WIRE STRUCTURES

Dana B. Carleton and William H. Simcoe, Trenton, N. J., assignors to The American Steel and Wire Company of New Jersey, a corporation of New Jersey

Application June 6, 1947, Serial No. 752,994

7 Claims. (Cl. 57—9)

1

This invention relates to apparatus for making stranded wire structures. Stranded wire structures is a generic term which includes wire rope, cables and strands and will be so used throughout the specification and claims. These cables consist of a plurality of strands which are composed of a plurality of wire components, the strands being wound or laid in longitudinal helices in an assembled radial relation about a similar wire strand or hemp rope core.

In making stranded wire structures, strand preforming devices are sometimes used with a standard stationary type closing die. In some cases when the preforming device is omitted, a rotary closing die is used to form the cable. Heretofore it was not thought feasible to combine the preforming device with a rotary closing die because of inherent difficulties in so combining them. We have found that by combining the two operations in a continuous manner and by driving the rotary closing die at the same rotational speed as the preforming head it is possible to satisfactorily combine these two types of machines.

It is an object of our invention to provide apparatus for making a stranded wire structure having improved physical characteristics.

This and other objects will be more fully apparent after referring to the following specification and attached drawings in which:

Figure 1 is a diagrammatic sketch of one form of apparatus for carrying out our invention;

Figure 2 is an enlarged perspective view of part of the apparatus of Figure 1 with certain parts broken away;

Figure 3 is a vertical sectional view taken through the shaft 16 to the right of plate 28 in Figure 2;

Figure 4 is a fragmentary view similar to Figure 1 showing a second embodiment of our invention;

Figure 5 is an enlarged sectional view of the preforming head of Figure 4; and

Figure 6 is a sectional view taken on the line VI—VI of Figure 5.

Referring particularly to Figure 1, the reference character 1 represents a rotatable tubular member which is supported horizontally in any suitable manner, such as by sets of rollers 2 equally positioned along its length. Equally spaced along the length of the tube 1 are a plurality of transverse spiders 3, between which are supported axially pivoted cradles 4. Rotatively mounted in the cradles 4 are the supply spools 5 on which the wire structures 6 are reeled.

5 Mounted axially on one end of tube 1 is a hollow mast 7 through which passes the core component 9 of the stranded wire structure. The mast 7 is provided with a hole 8 in its end in which the closing head of the present invention is mounted and secured by means of a key 19 and a setscrew 11. A series of lead sheaves 12 are mounted on the tube 1 radially about the mast 7. The tube 1 and related structure described above is that commonly used in making stranded wire structures.

10 When the closing machine is in operation, the wire structures 6 pass from their supply spools 5, through a system of guide sheaves and bushings to the lead sheaves 12 from whence they pass to the closing head of the present invention at which point they are twisted or assembled by the rotating action of the tube 1 to form the finished stranded wire structure 13. The assembled stranded wire structure 13 then passes to a haul-off mechanism 14 and thence to a take-up mechanism which winds the stranded wire structure on a storage reel 15. The wire structures 6 are pulled from their spools 5 through the closing head by the haul-off mechanism 14. The rate at which 15 the haul-off mechanism 14 pulls the wire structures 6 from their supply spools 5, together with the rotating speed of the tube 1, determines the helical length or "lay" of the wire structures 6 in the assembled form of the stranded wire structure 13.

20 Referring to Figure 2, which shows the details of our invention, the reference character 16 represents a steel shaft having an axial hole 17 therein which permits passage therethrough of the core component 9. The end of the shaft which is mounted in the mast 7 has a reduced portion 18 and a keyway 19 to receive key 10. Mounted on shaft 16, perpendicular to the axis thereof, is a circular steel guide plate 20 having an integral hub 21 threaded into which are set-screws 22 which hold it in its adjusted operative position. The guide plate 20 is adapted for longitudinal and radial movement along and around shaft 16. The face of hub 21 is provided with index marks 23 which together with a scribed reference line 24 on the surface of shaft 16 parallel to its axis, are used to indicate the radial adjustment of the guide plate 20. The reference line 24 is also provided with graduation marks 25 25 which are used to indicate the longitudinal adjustment of the guide plate 20. Mounted in guide plate 20 are plurality of equally spaced tungsten carbide guide bushings 26 which are arranged with their axes converging toward the entrance of the closing die so that in effect the axes ex-

tended define a right cone. The other end of shaft 16 is also provided with a reduced portion 27, having a steel circular dished plate 28 mounted thereon which is secured to shaft 16 by means of setscrews 29 threaded in a hub portion thereof. Located in plate 28 are a plurality of equally spaced holes 30 equal in number to the guide bushings 26. These holes are located radially about the axis of shaft 16 and equidistant from it with their axes forming an angle with the axis of shaft 16. These holes 30 serve to receive replaceable quills 31 which are adjustably mounted therein. The quills 31 consist of hardened steel cylinders in the surfaces of which are cut helical grooves 32. As best shown in Figure 3, each quill 31 has a pin 33 which facilitates its rotation in its mounting hole 30 and which together with scribed index marks 34 around the hole 30 are used to indicate the radial adjustment of the quill 31. Each quill 31 is locked in its operating position by means of a setscrew 35 which is threaded into the plate 28 directly above each of the holes 30.

The outside edge of plate 28 is provided with a shoulder 36 on which is mounted a replaceable steel spacer tube 37 which serves as the support for the rotary die assembly. The spacer tube 37 is provided with a plurality of inspection windows 38. Located between the windows 38 of the spacer tube 37 and cut into the internal surface thereof are longitudinal grooves 39. Mounted on the free end of the spacer tube 37 is the back chuck plate 40 of the rotary die assembly. The back chuck plate 40 consists of a circular steel plate having a large tapered central hole 41, around which are arranged a plurality of holes 42 which are in axial alignment with the grooves 39 in the spacer tube 37. The back chuck plate 40, spacer tube 37, and plate 28 are held in rigid assembly by means of bolts 43 which pass through the holes 42 in the back chuck plate 40, the grooves 39 in the spacer tube 37, and are threaded into companion tapped holes 44 in the plate 28. The back chuck plate 40 is also provided with two tapped holes 45, the axes of which are parallel to the axis of the shaft 16 and which have studs 46 threaded therein. The front chuck plate 47 is similar in size and shape to the back chuck plate 40 and is provided with two clearance holes 48 through which the studs 46 pass. Nuts 49 and wear washers 50 are mounted on studs 46 to permit longitudinal adjustment of the front chuck plate 47. Four mating steel jaw pieces 51 arranged parallel to the axis of shaft 16 are positioned between the chuck plates 40 and 47. The ends of the jaw pieces are tapered and mate with the tapered holes in the chuck plates 40 and 47. The jaws 51 are provided, on their interior surfaces, with rectangular longitudinal recesses 52 positioned in each of which is a flat cushion 53 made of leather or felt. Also positioned in the recess 52 of each jaw is a flat steel bearing or pressure plate 54 provided with a lip portion 55 on one end thereof. In the square cavity thus formed by the four pressure plates 54 are assembled the four segments of the rotary closing die 56. By this arrangement adjustment of nuts 49 will result in the radial convergence of the jaws 51 together with their companion cushions 53 and bearing plates 54, thereby compressing the segments of the rotary die 56 about the wire rope cable 13 being fabricated therein. Each of the four segments of the rotary die 56 has a plurality of grooves 57 therein so constructed that they will mate with the grooves 57

in the adjacent segments to form continuous helical grooves in the interior of the assembled die. The helical grooves, thus formed, correspond to the helical shape of the component strands 6 of the wire rope cable 13 contained therein. The pitch of these grooves is slightly greater than the pitch of grooves 32. The front chuck plate 47 is provided with two tapped holes 58 whose axes are parallel to the axis of the shaft 16. Threaded into the holes 58 are two studs 59 on which is positioned a flat steel thrust plate 60 which is provided with clearance holes 61 to permit passage of the studs 59 therethrough. A clearance slot 62 is provided in the center of plate 50 to permit passage of the completed cable 13. Hexagon nuts 63 and wear washers 64 mounted on the studs 59 permit longitudinal adjustment of the thrust plate 60 therealong. The thrust plate 60 may be brought into contact with the ends of rotary die 56 so that this adjustment permits the adjustment of the rotary die 56 along the longitudinal axis of the wire rope cable 13 and also permits the thrust plate 60 to absorb the longitudinal thrust occasioned by the drag of the cable 13 through the die 56 when the closing head is in operation.

In preparing for the production of a wire rope cable, the closing head of the present invention, with the quills 31 and parts 51, 53, 54, 56, 60, 63 and 64 removed, is mounted in the mast 1 of the closing machine and secured by means of key 10 and setscrews 11. The component strands 6 are conducted from their supply spools 5, over the lead sheaves 12, through bushings 26 in guide plate 20, thence through the quill holes 30 in plate 28 after which they pass through the tapered holes in the chuck plates 40 and 47. The ends of the strands 6 are then connected to a cable which has been reeved about the drums 10 of the haul-off mechanism 14 and secured to the reel 15 mounted in the take-up mechanism. The machine is put into operation and the rotating action of the tube 1 causes strands 6 to be twisted radially about the core component 9 thereby creating the general form of the assembled wire rope cable 13. The machine is stopped and the individual strands 6 are wrapped into the grooves 32 of the quills 31. Simultaneously with the wrapping procedure the quills 31 are inserted in the holes 30 of the plate 28 and rotated to their proper setting where they are secured by setscrews 35. It is to be understood that the rate at which the strands are being pulled through the closing head by the action of the haul-off mechanism 14 and the rotating speed of the tube 1 are properly coordinated, through the medium of gearing or other means, to produce a lay of the desired pitch. The selection of the quills 31 to be mounted is determined by the lay and the diameter of the finished wire rope cable 13 being fabricated. After the quills have been set in their operating position, the guide plate 20 is adjusted longitudinally and radially until the component strands 6 passing from the guide bushings 26 to the quills 31 enter the quill grooves 32 in a tangential manner. The machine is again put into operation and the preformed strands are twisted together to form a short section of preformed wire rope cable of the desired lay. The machine is again stopped and the rotary die is assembled about the wire rope cable 13 thus formed. The lay and rope diameter also determine the selection of the rotary die. It is imperative that the quills and rotary dies be matched for each condition of cable diameter and lay length. In as-

sembling the rotary dies three of the jaw pieces 51 are positioned between the chuck plates 40 and 47. Three of the cushions 53 and three of the pressure plates 54 are then positioned in the recesses 52 of these jaw pieces 51. The four segments of the rotary die 56 are next inserted in the cavity thus formed and assembled radially about the wire rope cable 13. The segments of the rotary die are assembled so that the inner ends of the dies fall at the "point of twist" and are also in contact with the lip portion 55 of the pressure plates 54. The rotary die is then converged about the cable by rotation of the nuts 49 on the studs 46. After the dies have been converged, the thrust plate 60, washers 64 and nuts 63 are mounted on the studs 59. Thrust plate 60 is then advanced longitudinally along the wire rope cable 13, by rotation of nuts 63, until it is in contact with the ends of the rotary dies 56. The machine is again placed in operation and minor adjustments, if necessary, are made until the rope emerging from the die is free from any die or scratch marks and the openings between the component strands 6 of the completed cable are equalized. The closing pressure of the rotary die 56 is then established by further rotation of nuts 49 and the machine is put into operation and the entire required length of wire rope cable 13 is fabricated.

It is to be understood that the distance from the point of emergence of the strands from the preforming devices to the point of twist or convergence will vary in the approximate range of from 4 to 12 times the diameter of the wire rope cable for any given diameter. Provision is made for varying this distance through the medium of a series of replaceable tubes 37 of various lengths, which together with the longitudinal adjustment of the dies 56 permit the dies 56 to be accurately positioned at the "point of twist" for all requirements within this range.

The present invention permits the simultaneous use of a preforming device and a rotary closing die, and further permits the incorporation, of all the beneficial results arising from the use of these devices, into any wire rope cable fabricated thereon. These results are achieved by preforming the component strands in the preforming section and then delivering these preformed strands to the rotary die at their point of convergence without distorting the shape of the strands and while maintaining the strands in their proper radial and planetary relationship about the core component.

The stranded wire structure so produced will be relatively free from residual stresses, the strands on the core will be closely and evenly spaced, free of die marks, round and will have a higher modulus of elasticity than previous stranded wire structures of comparative material.

Figure 4 discloses schematically a slight modification of our invention. In this embodiment the quill type preforming head is replaced by a roller type preforming head of the type disclosed in the patent to Blamire, No. 1,945,799. This type of preforming head has a set of three rollers 67 for performing each strand 68. The preforming head 66 is provided with a three arm basket 69 which encloses the rollers 67. The basket 69 is bolted to the end plate 70 which is provided with openings through which the strands 68 pass. The end plate 70 is fastened to an adapter 71 which fits within the bore of the mast 72. A rotary die holder 73 of the type disclosed in Fig-

ure 2 is fastened to the end of the preforming head 66. The rollers 67 are rotatably mounted on rotatable plates 74, 75 and 76. The outer plates 74 and 76 are keyed to a hollow shaft 77 through which passes the central strand 68. The intermediate plate 75 is rotatably mounted upon an inner collar 78 which is keyed to the shaft 77. The plate 75 has an inwardly extending flange 79 on one side and a retaining ring 80 on the other side between which is embraced a peripheral rib on the collar 78. Bolts 81 are provided to hold the retaining ring 80 in place. The outer ring 75 may be adjusted rotatably upon the inner collar 78 by means of a worm 82 mounted on a shaft 83 which is rotatably supported in bearings 84 carried by the collar 75. The worm 82 engages teeth 85 on the periphery of collar 78. The outer plates 74 and 76 are adapted to be moved axially along the shaft 77 by means of screws 86 and 87 which pass through threaded apertures in the collars or carriers 74 and 76. The ends of each of the shafts are oppositely threaded, so that when the shafts are turned in one direction, the collars 74 and 76 are simultaneously moved toward the middle carrier 75, and when rotated in the other direction, the carriers are moved simultaneously away from the central carrier 75. The shafts are formed without threads at their middle portions and pass through apertures in the inner collar 78. Collars 88 are provided on the shafts 86 and 87 on each side of the inner collar 78. Each screw 86 and 87 is provided with a pinion 89 secured to its inner end which are arranged to engage with an interior ring gear 90. The gear 90 is secured around the periphery of a collar 91 which is rotatably seated upon the shaft 77. The shaft 77 rotates with a guide plate 92 which is bolted to the end plate 70. Otherwise the operation of the machine is the same as that described in Figures 1 to 3.

While two embodiments of my invention have been shown and described, it will be apparent that other adaptations and modifications may be made without departing from the scope of the following claims.

We claim:

1. In a machine for making stranded wire structures from a plurality of components, the combination including a rotatable guide plate having a plurality of guides mounted therein, a rotatable plate spaced from said guide plate and having a plurality of openings therethrough arranged at an angle to the axis of rotation, a quill in each of said openings, each of said quills having a helical groove in the periphery thereof, means for adjusting the position of said quills in said openings, a hollow shaft for supporting said plates, a pair of chuck plates, means for fastening one of said chuck plates to the rotatable plate, means for moving the second of said chuck plates to and from the first chuck plate, each of said chuck plates having opposed axial tapered holes therein, a plurality of jaw pieces in said tapered holes, each of said jaw pieces having tapered sides mating with the tapered sides of the tapered holes, a plurality of die segments mounted in the cavity formed by the jaw pieces, a plurality of matching helical grooves in the die segments, and means for rotating the guide plate, rotatable plate and dies at the same angular velocity.

2. In a machine for making stranded wire structures according to claim 1, a thrust plate adjustably supported by the second chuck plate and bearing against said dies, and means for

moving the thrust plate with respect to the second chuck plate to vary the distance between the quills and the die.

3. In a machine for making stranded wire structures from a plurality of components, the combination including a rotatable preforming head for forming helices in the individual components, a rotary closing die, means for pulling the components through the preforming head and then through the closing die, and means for rotating the preforming head and die at the same angular velocity, said preforming head comprising a rotatable plate having a plurality of openings therethrough arranged at an angle to the axis of rotation, a quill in each of said openings, each of said quills having a helical groove in the periphery thereof, and means for adjusting the position of said quills in said openings.

4. In a machine for making stranded wire structures from a plurality of components, the combination including a rotatable preforming head for forming helices in the individual components, a rotary closing die, a plurality of helical grooves in the closing die, the pitch of said grooves being greater than the pitch of the helices originally formed in said components, means for pulling the components through the preforming head and then through the closing die, and means for rotating the preforming head and die at the same angular velocity.

5. In a machine for making stranded wire structures from a plurality of components, the combination including feed means rotatable about a longitudinal axis for supporting the individual components in spaced relationship, a rotary closing die toward which the components converge from the feed means, a rotary preforming head located between the supporting means and the closing die for forming helices in the individual components, said preforming head comprising means for supporting each component at a plurality of points as the components converge toward the closing die, means for pulling the components through the preforming head and then through the closing die and means for rotating the preforming head and die at the same angular velocity.

6. In a machine for making stranded wire structures from a plurality of components, the combination including a rotatable preforming head for forming helices in the individual components, a pair of chuck plates, means for moving one of said chuck plates to and from the other of said chuck plates, each of said chuck plates having opposed axial tapered holes there-

in, a plurality of jaw pieces in said tapered holes, each of said jaw pieces having tapered sides mating with the tapered sides of the tapered holes, a plurality of die segments mounted in the cavity formed by the jaw pieces, a plurality of matching helical grooves in the die segments, and means for rotating the preforming head and dies at the same angular velocity.

7. In a machine for making stranded wire structures from a plurality of components, the combination including a rotatable preforming head for forming helices in the individual components, a rotary closing die, means for pulling the components through the preforming head and then through the closing die, and means for rotating the preforming head and die at the same angular velocity, said preforming head comprising a series of rotatable plates having a plurality of grooved rollers rotatably mounted on the circumferences thereof, the said rollers having their axes perpendicular to an angle to the axis of rotation of the said plates, the outermost of the said plates being mounted for axial adjustment relative to an intermediate plate and an intermediate plate being mounted for circumferential adjustment relative to the outermost plates.
